John E. Jackson
his Attorney.

UNITED STATES PATENT OFFICE

2,187,319

BEARING PILE CONSTRUCTION

Gerald G. Greulich, Mount Lebanon, Pa.

Application November 23, 1938, Serial No. 242,089

1 Claim. (Cl. 61—53)

The present invention relates to load-bearing pile constructions, and particularly, to the formation of enlargements to the normal bearing pile section only in that portion of the pile which is in firm load-carrying soil.

An object of the present invention relates to the formation of a bearing pile having tapered timber lagging members secured to a tapered body member.

Other objects and advantages will become apparent as the description proceeds and reference is had to the accompanying drawing, in which:

Figure 1 is an elevation showing a bearing pile constructed from timber to which tapered timber lagging members are secured;

Figure 2 is a section on line II—II of Figure 1; and,

Figure 3 is a section on line III—III of Figure 1.

In the drawing, the bearing pile comprises a tapered main body portion 2, upon which is secured, in any conventional manner, one or more timber lagging members 3.

The main body portion 2 tapers gradually from its top portion to its lower or penetrating end, so that its cross-section decreases in width from its top to its bottom. The tapered lagging members, which are shown as comprising timber piles, are provided, upon one face, with a tapered surface, with the greatest cross-sectional area of each lagging member being at its top and the taper being gradually downward to a point adjacent the penetrating end of the main body portion 2, so that the lower end of each lagging member has a less cross-sectional area than its top portion. The timber lagging members 3 are

secured to the main body portion 2 by the bolts 4 which pass through the lagging on both sides and through the main body portion of the bearing pile and secure by nuts 5.

Under the present construction, the use of tapered pieces of lagging, characterized by having their top portions enlarged, results in an increase in the angle of taper of the bearing pile which produces greater load-carrying capacity of the same, due to the increase in soil displacement.

While I have shown and described a specific embodiment of the present invention, it will be seen that I do not wish to be limited exactly thereto, since various modifications may be made without departing from the scope of the invention, as defined by the following claim.

I claim:

A bearing pile comprising a tapered main body portion including a penetrating point, said tapered main body portion having a cross-sectional area decreasing gradually from its top to its penetrating point, and lagging members secured to said main body to provide a tapered enlargement extending only over that portion of said bearing pile which is in firm load-carrying soil, said lagging members comprising timber piles, each provided with an outer tapered surface with the greatest cross-sectional area of each lagging member being at its top and the taper being gradually downward to a point adjacent the penetrating end of said main body member, thereby increasing the angle of taper of the bearing pile and providing for greater load carrying capacity thereof.

GERALD G. GREULICH.
